UNITED STATES PATENT OFFICE.

WILBER THOMAS, OF QUINCY, ILLINOIS.

DESIGN FOR A FENCE-PICKET.

SPECIFICATION forming part of Design No. 13,926, dated May 22, 1883.

Application filed November 20, 1882. Term of patent 14 years.

To all whom it may concern:

Be it known that I, WILBER THOMAS, a citizen of the United States, residing at Quincy, in the county of Adams and State of Illinois, 5 have invented a new and original Design for Fence-Pickets and the like, of which the following is a specification, reference being had to the accompanying drawings.

This invention consists in a new, useful, and 10 ornamental design for fence-pickets, palings, and the like, which is adapted more especially to that class of fence-pickets that are held by encircling twists of wire.

In the drawings, Figure 1 is a perspective 15 view of a portion of a fence constructed with my ornamental pickets. Fig. 2 is a cross-section thereof, and Fig. 3 is a like view illustrating a modification.

Referring to the drawings, A designates the 20 pickets, each of which is formed with an enlarged central portion, a , forming a central ridge at each side, having its entire surface or only part thereof in curved contour. At each side of these ridges is formed a depressed portion 25 or groove, a' , adjoining which are formed enlarged side edges, a^2 . The latter are in curved contour around their entire surface, or have their ends flattened, similar to the form presented in the modification shown in Fig. 3.

Ornamental pickets as herein formed 30 part to the fence an especially attractive and pleasing appearance, and by reason of the central curved enlarged portion possess great strength, that renders them safe from accidental breakage. In the modification this 35 strength and attractive contour are retained, while a much smaller paling in cross-section is produced and economy in material secured.

I claim as my invention—

1. An ornamental design for fence-pickets 40 and the like, consisting in the picket formed with a central enlarged portion having depressions or grooves at each side, which are adjoining enlarged side edges, said enlarged central portion and edges having their surfaces in 45 entirely or partly circular contour, as set forth.

2. The herein-described design for fence-pickets and the like, as set forth.

In testimony that I claim the foregoing as 50 my own I have hereto affixed my signature in presence of two witnesses.

WILBER THOMAS.
